CHESS PIECE SET FOR CHINESE CHESS

Wah J. Sheck, Rockville, Md., assignor to
Gemini Products, Inc., Wheaton, Md.

Filed July 27, 1973, Ser. No. 383,112

Term of patent 14 years

Int. Cl. D21—01

U.S. Cl. D34—5 CH

FIG. 1.

FIG. 2.

FIG. 1 is a plan view of a chess piece set for Chinese chess showing my new design; and

FIG. 2 is a typical side elevational view of the chess pieces.

I claim:

The ornamental design for a chess piece set for Chinese chess, substantially as shown and described.
